Patented June 28, 1927.

1,634,228

UNITED STATES PATENT OFFICE.

FRANK B. ALLEN, OF LOWER MERION TOWNSHIP, MONTGOMERY COUNTY, PENNSYLVANIA, ASSIGNOR TO FRANK H. DUNBAR, OF CLEVELAND, OHIO.

ASH-HANDLING EQUIPMENT.

Original application filed March 21, 1921, Serial No. 454,321. Divided and this application filed April 9, 1926. Serial No. 160,894.

My invention relates to apparatus for handling ash or other material having similar form; and apparatus for handling such material whether hot or cold. My invention 5 is shown in connection with an ash producing furnace.

Up to the present time, the operators of large power plants have been seriously effected by defective ash controlling apparatus. The larger the plant the more serious and aggravated have the troubles arising 10 from this source of the plant become.

Almost any mediocre means for handling the ash of a small plant will give reasonable 15 satisfaction, but as the size of the plant is increased, and with the coming of automatic stokers and forced drafts, the matter of handling the large volume of ash in a heated condition as a result of the forced draft, together 20 with the necessity of using water for cooling the ashes, the matter has become more and more serious and the deficiency of the old type of equipment has become more and more noted and accentuated. The problem 25 that confronts the installer and the manufacturer of this type of equipment is not only a question of effectiveness in mechanism but likewise a question of cost of construction, and up to the present time the combination 30 of these two features has not been obtained as it has in the present invention.

Until very recently, a boiler containing five thousand square feet of heating surface, 35 for example, was called a 500 H. P. boiler. Today the same boiler is operated to produce 1000 to 1500 or even 2000 boiler H. P. To obtain this result, resort has been had to forced draft which incidentally produced 40 ash that is more difficult to handle than that produced without forced draft. The difficulty of handling the ash is further aggravated by the increasing tendency to use coals of lower grade, and is further aggravated 45 by the fact that whereas formerly the size of a boiler seldom exceeded 500 H. P., now they are practically always between 1400 and 2500 H. P.

The net result of all of these new conditions, is that whereas formerly in a large installation about $3\frac{1}{2}$ tons of clean, disintegrated ashes had to be removed from a single

boiler daily, today from 20 to 50 tons of clinkered ash, highly heated, must be handled from each boiler. When it is further 55 considered that in a modern station there are provided from ten to twenty such boilers, the difficulty of handling the ash becomes apparent.

In meeting these conditions and solving 60 them, the inventor has produced the invention described herein, among the objects of which are the following:

To provide an ash hopper in which the sides diverge;

To provide a frame for the gate which is directly attached to the steel ribs of the hopper;

To provide a hopper composed of spaced, depending ribs carrying a gate frame at the 70 lower ends thereof, the ribs serving as supports to which wall forming plates are secured;

To provide hopper parts which can be readily manufactured in small, easily handled parts and erected at the plant where they are to be used with the minimum of labor, time and effort;

To provide a hopper construction in which cast iron and steel parts are used in such a 75 manner as to obtain the benefit of the advantages characteristic of each material while avoiding the disadvantages;

To provide an improved hopper and associate mechanism;

To provide other details of improvement tending to increase the efficiency and serviceability of a hopper and associate mechanism of the above character.

To accomplish the foregoing and other useful ends, my invention comprises means hereinafter more fully set forth and claimed.

This application is a division of my co-pending application Serial No. 454,321, filed March 21, 1921.

Referring to the drawings:

Fig. 1 is a perspective view from below, partly in section, of one form of hopper embodying my invention; and

Fig. 2 is a similar view from above of a 100 similar device.

Referring more in detail to the drawings, it will be understood that the hoppers shown in Figs. 1 and 2, for example, are associated

with the grate of a boiler (not shown) which may be of an under-feed forced draft type. These hoppers are aligned along the front of the grate, into which the ashes and clinkers from the furnace are collected. The hopper may terminate in a single gate or it may have more than one terminal. Each terminal is provided with a gate frame in which there may be provided one or more gates. Each hopper 1 is suspended from overhead supporting members 2 which in the figures are shown as constituting floor beams for the boiler house. Each hopper 1 is preferably composed of a plurality of spaced ribs 3 secured at their upper ends to the members 2, as by riveting, bolting or any suitable means, and depending from the members 2 in a more or less side by side parallel relation except at the corners of the hopper where, if desired, ribs 3^a may be disposed at an angle to the other ribs 3. At the lower ends of the ribs 3 and 3^a is carried a gate frame 4. Any suitable securing means, such as bolts, rivets or the like, may be employed to secure the gate frame 4 to the lower ends of the ribs 3 and 3^a. Each frame 4 preferably comprises a rectangular frame of cast iron of suitable size and shape to surround the discharge opening 5 in the lower part of the hopper, and where two hopper discharge openings are disposed in side by side position, as is shown in the drawings, a gate frame 4 may be provided for each opening.

35 Each frame 4, as shown herein, is provided with a top, horizontal wall 7 which is secured to the ribs 3 and 3^a, a bottom, horizontal wall 8 and webs 9 connecting the two walls. The walls 8 serve as tracks for the rollers 10 of a door 11 which constitutes the movable closure for the discharge opening 5. A cylinder 12 supported at one end of the door 11, and in the modification shown by the figures between two adjacent hoppers 1, is equipped with a piston (not shown) and a connecting rod 13 which is secured to a bracket 16 on the door by means of which parts the door may be actuated into and out of open and closed position with respect to the discharge opening 5. The cylinder 12 is shown supported by a frame-work including side rails 14 which are secured to adjacent frames 4 and which constitute tracks for rollers 10 of the doors 11, and cross bars 55 15 to which the cylinder 12 is secured.

A sectional metal wall, composed of a plurality of similar plates 17, is disposed within and secured to the uprights 3 and 3^a. Each plate 17 may be assembled independently of the other plates and secured to the ribs 3 and 3^a in any suitable manner, as by bolts, rivets or the like. Each plate 17 has on its inner surface an inwardly projecting flange 18 upon which lining blocks 19, composed of refractory material, may rest.

These blocks are held in position, as shown in Fig. 2, by means of castings 20 secured to the ribs 3 and shaped to seat in dovetailed grooves in certain of the blocks 19. The side edges of the blocks which cooperate with the castings 20 are formed at an angle to the inner faces thereof to overlap correspondingly shaped edges of blocks 19^a disposed between the adjacent rows of blocks 19.

75 It will be understood by those skilled in the art that the steel ribs 3 and 3^a may be readily fabricated by a steel mill, since they may conveniently consist of T-sections; and, furthermore, that the wall plates 17 may readily be constructed of cast iron. The assembly of the ribs 3, frames 4 and plates 17 may be carried out quickly with a few men and without extensive hoisting equipment or delay. The refractory blocks 19 and 19^a may be assembled after the metal parts of the hopper are in position and may be disassembled with a minimum of effort.

80 It will also be understood by those skilled in the art that I have provided load carrying parts of high tensile strength and composed of steel but have so disposed these parts that they are protected from direct contact with acid liquids within the hopper, such as are formed by bringing water into contact with hot sulphur containing compounds in the coal ashes in the hopper; and that, furthermore, I have provided corrosion resisting cast iron parts of adequate strength for the purpose disposed to contact 90 with the acid liquids and where strength is second in importance to resistance to corrosion. The plates 17 and the frames 4 are acid resistant and still strong enough to carry the loads imposed on them.

95 It will be understood from the foregoing description and from the drawings, that I have a skeleton structure for a hopper including the overhead supporting members 2, the depending rib members 3 and 3^a, the gate frame 4 and the wall plates 17.

100 It will be seen that I contemplate the provision of a hopper having a steel frame within which I support the walls of the hopper. The steel ribs may be secured to the girders of the building or superstructure in any suitable manner. In the old type of hopper in which the walls converge, the ashes and clinkers form an arch that obstructs the passage of the ashes from the hopper into the car. The diverging walls, however, insure against this difficulty.

105 I have found that satisfactory results are obtained when all of the sides of the hopper are made to flare as they approach the lower mouth, but the hopper may be made so that one wall only slopes away from the opposite wall, in other words, I provide a hopper in which the area increases as the lower mouth is approached.

Having thus described my invention, what I desire to secure by Letters Patent is defined in what is claimed.

I claim:

- 5 1. In a hopper having a discharge opening in its lower portion, in combination, a metallic skeleton structure for a hopper comprising overhead supporting members, spaced ribs depending from said members,
- 10 10 a gate frame carried by the said ribs at their lower ends, metal wall plates supported by the said skeleton structure and secured to the inside of the ribs, the said wall plates being composed of corrosion resistant material.
- 15 2. In hopper construction, in combination, a metallic skeleton structure for a hopper comprising overhead supporting members, spaced ribs depending from said members,
- 20 20 a gate frame carried by the said ribs at their lower ends, metal wall plates supported by the said skeleton structure and secured to the inside of the ribs, the said ribs being composed of material having relatively high
- 25 25 tensile strength as compared with the material of the plates, the said ribs being dis-

posed out of direct contact with acid liquids formed in the hopper.

3. In a hopper construction, in combination, adjacent hoppers each having a discharge opening in its lower portion, each hopper comprising overhead supporting members, depending members secured at their upper ends thereto and carrying a gate frame at their lower ends, hopper wall forming plates secured to the said depending members, and means including parallel track-for ning rails disposed between and connected to the gate frames of two adjacent hoppers.

4. In hopper construction, in combination, floor beams, a hopper suspended beneath and supported from the said floor beams, the said hopper comprising spaced ribs secured at their upper ends to the floor beams, a gate frame secured to the lower ends of the said ribs, and metal wall plates disposed within and secured to the said ribs.

In testimony whereof I hereunto affix my signature this 7th day of April, 1926.

FRANK B. ALLEN.
